Filed July 31, 1972, Ser. No. 276,426

Term of patent 7 years

Int. Cl. D6—04
U.S. Cl. D6—113

FIG. 1 is a top plan view of the horizontally mounted rack for a plurality of lawn chairs showing my new design;

FIG. 2 is an end elevational view thereof;

FIG. 3 is a bottom view thereof;

FIG. 4 is a bottom view similar to FIG. 3 and showing the rack in a collapsed condition for packaging;

FIG. 5 is a side elevational view thereof; and

FIG. 6 is an isometric view thereof.

I claim:

The ornamental design for horizontally mounted rack for a plurality of lawn chairs or the like, substantially as shown and described.
